UNITED STATES PATENT OFFICE.

HENRY J. GUENTHER, OF NEWARK, NEW JERSEY, ASSIGNOR TO UNITED LEATHER GOODS CO., OF NEWARK, NEW JERSEY, A FIRM CONSISTING OF THEODORE H. GOTISAR AND HENRY J. GUENTHER.

BRIEF BAG OR CASE.

1,322,785.

Specification of Letters Patent. Patented Nov. 25, 1919.

Application filed May 27, 1918. Serial No. 236,699.

To all whom it may concern:

Be it known that I, HENRY J. GUENTHER, a citizen of the United States, residing at Newark, in the county of Essex and State 5 of New Jersey, have invented certain new and useful Improvements in Brief Bags or Cases; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, more particularly, to improvements in hand-bags and a novel frame and locking means therefor; and the invention has reference, more particularly, to a novel brief-case, in which 20 persons of professionals, as lawyers, musicians, etc., can be placed in a flat condition, with a view of providing a case into which the various papers or sheets of music can be easily and quickly placed, and just as readily removed without inconvenience to the 25 person desiring to take from the pockets of the case, one or more sheets of paper or sheets of music.

30 The present invention has for its principal objects to provide a novel and simply constructed brief-case, comprising a receptacle or body of leather, or the like, said receptacle or body being provided with any desirable number of receiving pocket, in 35 which the papers or sheets of music can be disposed in flat condition; and, the present invention has for its further object to provide the mouth of the receptacle or bag-body with suitable frame-members and a locking means in connection therewith, said 40 frame-members or section extending laterally, and preferably along the marginal edge-portions of the opening or mouth of the receptacle or bag-body, so as to act as a 45 reinforcing or stiffening means, to retain the bag-body in its proper shape, against distortion, when carrying the brief-case and when the same is filled with many papers of considerable weight.

50 The invention has for its further object to provide a brief-case of the general character hereinafter set forth, in which when it is desired to remove or replace papers,

the flap-members of the mouth of the bag-body are readily maintained in their opened 55 relation, without falling back into a position which would close or obstruct the opening, so that at all times the upper open portions of the various pockets are presented to the operator in their open positions for the 60 insertion or withdrawal of the desired paper or papers from any one of the pockets.

Other objects of the present invention not at this time more particularly enumerated 65 will be clearly understood from the following detailed description of the said invention.

With the various objects of the present invention in view, the said invention consists, primarily, in the novel brief-bag or case 70 hereinafter more fully set forth; and, the invention consists, furthermore, in the novel arrangements and combinations of the various devices and parts, as well as in the details of the construction of the said parts, 75 all of which will be more fully described in the following specification and then finally embodied in the clauses of the claims which are appended to and which form an essential part of the said specification. 80

The invention is illustrated in the accompanying drawings, in which:—

Figure 1 is a view of a brief-bag or case, embodying the principles of the present invention, said view representing in elevation 85 what may be termed the rear face of the bag or case; and Fig. 2 is a front elevation of the said brief-bag or case, illustrating a fragmentary portion of the latter, and both of said views representing the bag or case 90 closed.

Fig. 3 is an elevation of the brief-case or bag, with the upper portions of the bag or case represented in their opened relations; and Fig. 4 is a top view of the same, as 95 represented in said Fig. 3.

Fig. 5 is a transverse vertical section of the brief-bag or case, said section being taken on line 5—5 in said Fig. 3; and Fig. 6 is a detail sectional representation taken on line 6—6 in said Fig. 5, said view being made on an enlarged scale.

Similar characters of reference are employed in all of the said above described views, to indicate corresponding parts.

Referring now to the several figures of

the drawings, the reference-character 1 indicates the complete brief-bag or case, the same comprising a main body 2, made of leather or other suitable material, and provided between its sides and ends with any desirable number of separating or parting members 3, so as to provide the paper-receiving pockets 4.

As shown more particularly in Fig. 5 of the drawings, I have indicated the two sides of the bag-body or case, respectively, by the reference-characters 5 and 6, the upper portion of the side 5 being provided with a mouth-closing flap 7, and the upper portion 10 of the side 6 being likewise provided with a mouth-closing flap 8, both of said flaps extending laterally entirely across the upper portions of the respective sides, and being adapted to be brought vertically into adjacent 15 and closed relation with one another over the open parts of the pockets, or being adapted to be brought into an open relation, such as is represented in Figs. 3, 4 and 5 of the drawings.

25 Suitably secured along the upper marginal edge-portion of the flap 7, and extending laterally the entire distance of the same, is a reinforcing frame-section or member made of metal, said section or member 30 being angular in cross-section, so as to provide the upper face-plate or member 9 and the downwardly extending flange-member 10 to which the flap 7 is secured by means of pins or rivets 11, or other suitable fastening means, passing through a suitable and laterally extending inlay, as 12, as will be clearly evident from an inspection of Figs. 1 and 5 of the drawings. At its respective ends, the said frame-section or member is formed with angularly bent portions, as 13, 35 which provide strengthening or reinforcing corners.

Suitably mounted upon the face-plate or member 9 are handle-loops, as 14, with which are connected in the usual manner, 45 the end-portions of a handle 15. Also suitably secured to the said frame-section or member, in any usual manner, is a lock, as 16, of any desired construction, the casing of which is provided with the usual hasp-lug 50 receiving openings 17, substantially as shown in Figs. 3 and 4 of the drawings. At or near the respective ends of the face-plate of the said frame-section or member, there are suitably mounted the clamp-plates 55 18, with each of which are pivotally connected suitable clasping members or clamps, as 19, the purposes of which are well-known and self-evident from an inspection of the several figures of the drawings. Each 60 clamp-plate 18 may also be provided with an angular end-piece, as 20, for the purpose of protecting and reinforcing the respective end-portions of the frame-section or member, as will be clearly understood.

65 In a similar manner, there is secured along

the upper marginal edge-portion of the flap 8, and extending laterally the entire distance of the same, a second reinforcing frame-section or member made of metal, said section or member also being angular in cross-section, so as to provide the upper face-plate or member 22 and the downwardly extending flange-member 21 to which the flap 8 is secured by means of pins or rivets 23, or other suitable fastening means, passing through a suitable and laterally extending inlay, as 24, as will be clearly evident from an inspection of the several figures of the drawings. At its respective ends there are secured by means of pins or rivets, as 25, or other suitable fastening means, as will be seen from an inspection of Figs. 2 and 6, certain reinforcing, as well as ornamental corner-plates, as 26, each plate being bent, as at 27, about the end-edges of the frame-section and inlay, as 28, resting upon and being suitably clamped against the said inlay, substantially as shown. Suitably connected with this last-mentioned 90 frame-section or member is a suitably formed hasp, the hasp-lugs 29 of which are adapted to be brought into holding or locked engagement with the mechanism of the lock 16 when the flaps 7 and 8 of the brief-bag or case are brought into their closed relation. When thus closed, the frame-section or member which is attached to the flap 8 moves directly beneath the frame-section or member which is attached to the flap 7, the bent portions 27 of the respective plates 26 entering back of the angularly bent portions or members 18, to thereby provide a rigidly closed relation of the two frame-sections, and preventing any distortive movement of the said frame-sections laterally with relation to one another, as will be clearly evident.

When the brief-bag or case is held in one hand by the handle 15, or grasped by its bottom portion in one hand, and the frame-sections are released from mutual engagement, the flaps 7 and 8 fall outwardly by gravity, thus not only exposing the mouths of the pockets 4, but also, by reason of the weight of the flaps and their frame-sections, 110 causing the mouths of said pockets 4 to open out or extend, thus rendering the contents of any single pocket very easily and conveniently accessible.

Of course I am fully aware that some 120 changes may be made in the general arrangements and combinations of the several devices and parts, as well as in the details of the construction of the said parts, without departing from the scope of the present invention as set forth in the foregoing specification. Hence, I do not limit my present invention to the exact arrangements and combinations of the various devices and parts as described in the said specification, 125 130

nor do I confine myself to the exact details of the construction of the said parts as illustrated in the accompanying drawings.

I claim:

- 5 1. A brief-bag or case comprising a body consisting of normally straight sides and interdisposed parting members, arranged to provide pockets, the upper portions of said straight sides extending substantially above
- 10 said parting members so as to provide oppositely disposed closing flaps, reinforcing frame-sections connected with said flaps, said frame-sections being adapted to be brought into closed relation, and means connected with said frame-sections for maintaining the closed relation of said frame-sections.
- 15 2. A brief-bag or case comprising a body consisting of normally straight sides, parting members interposed between said sides to provide pockets, gusset members interconnecting the bottom and end portions of said parting members and sides, said sides being provided with free flexible flaps projecting
- 20 upwardly beyond the upper limits of said parting members and said gusset members, frame-sections connected with the upper longitudinal edges of said flexible flaps, and means for holding said frame-sections
- 25 in closed relation, said flaps being adapted to fall outwardly by gravity when said frame-sections are released to freely expose and open the mouths of said pockets.
- 30 3. A brief-bag or case comprising a body consisting of normally straight sides, parting members interposed between said sides to provide pockets, gusset members interconnecting the bottom and end portions of said parting members and sides, said sides being
- 35 provided with free flexible flaps projecting
- 40 upwardly beyond the upper limits of said

parting members and said gusset members, frame-sections connected with the upper longitudinal edges of said flexible flaps, catch devices connected with said frame-sections for holding the same together to close said flaps over the mouths of said pockets, and a handle-portion connected with one of said frame-sections, said flaps being adapted to fall outwardly by gravity when said frame-sections are released to freely expose and open the mouths of said pockets.

4. A brief-bag or case comprising a body consisting of normally straight sides, parting members interposed between said sides to provide pockets, gusset members interconnecting the bottom and end portions of said parting members and sides, said sides being provided with free flexible flaps projecting upwardly beyond the upper limits of said parting members and said gusset members, frame-sections connected with the upper longitudinal edges of said flexible flaps, means for preventing endwise distortion of said frame-sections relative to each other when closed together, catch devices connected with said frame-sections for holding the same together to close said flaps over the mouths of said pockets, and a handle-portion connected with one of said frame-sections, said flaps being adapted to fall outwardly by gravity when said frame-sections are released to freely expose and open the mouths of said pockets.

In testimony that I claim the invention set forth above I have hereunto set my hand this 25th day of May, 1918.

HENRY J. GUENTHER.
